TER HAFTUNG, OF HAMBURG, GERMANY.

MACHINE FOR WHETTING RAZOR BLADES.

1,408,298.

Specification of Letters Patent. Patented Feb. 28, 1922.

Application filed May 12, 1921. Serial No. 468,969.

To all whom it may concern:

Be it known that I, ERICH KARL FRIEDRICH HEYDENBLUTH, a citizen of Germany, residing at Hamburg, Germany, have invented certain new and useful Improvements in Machines for Whetting Razor Blades, (for which application has been made in Germany April 29, 1920,) of which the following is a specification.

10 The present invention refers to a machine for whetting, honing and stropping razor blades, in which a number of blades are carried along by an endless metal band, past whetting disks in such manner that the 15 blades are honed and stropped in one operation.

According to this invention the endless band together with the razor blades is drawn between two immovable rigid guide-rails in 20 such manner that these rails prevent any oscillation or vibration of the blades, while being operated upon by the whetting disks, with the object of producing a keen sharp edge on one or both sides of the blades.

25 In the drawing a machine is shown to suitably carry out the present invention.

Fig. 1 is an elevation of the machine, parts being broken away and other parts being shown in section for sake of clear illustration.

30 Fig. 2 is a cross section of the machine shown in Fig. 1 drawn to a large scale.

Fig. 3 is a cross section of the guiding rails drawn to a still larger scale.

35 Fig. 4 is a plan view of the rails partly in section.

Fig. 5 is a longitudinal section of the lower rail and

40 Fig. 6 shows a driving bolt in three different positions.

In the machine selected to illustrate the invention there is provided, a frame *a*, at the ends of which two disks or drums *b* are journaled around which runs an endless metal 45 band *c* preferably of steel, as is well known per se. On the upper part of the frame *a* a rail *d* is firmly attached, provided on its upper side with a longitudinal shallow groove *f*, of the breadth and the depth of the endless band and a deeper narrower groove *g* for the purpose hereinafter described. Above the rail *d* a second rail *h* is also firmly attached 50 to the frame *a* by any well known means. The

two rails *d* and *h* are such a small distance *k* apart, corresponding to the thickness of 55 the razor blades that they are adapted to allow these blades *m* to pass between them. The endless band *c* is provided with a number of holes *o*, and similar holes *o*¹ are provided in the blades *m* at such distance apart 60 that two holes are in each blade. Into the holes *o* of the metal band *c* and the holes *o*¹ of the blades fit the driver bolts *n* guided with their lower part in the groove *g* of the lower rail *d* and with the upper part in the 65 groove *i* of the upper rail. The driver bolts, which fit in the grooves *g* and *i* are provided with flanges *n*¹ at the lower end to prevent the rotation within the groove *g*. These 70 bolts are inserted into the endless band from inside out in such manner that the upper part of the bolts projects out. Before entering the space between the rails *d* and *h* the blades *m* to be whetted are filed on the bolts *n*, as is shown in Figs. 4 and 5, so that 75 each blade is held by two bolts and on forward movement of the band *c* are driven along between the two rails *d* and *h*. Above and below the rails *d* and *h* a convenient 80 number of whetting disks are journaled alternatively to the right and the left of the centre line of the rails in sets of two, four or more disks. Thus in the machine selected for illustration, three sets of disks *p*, *q* and *r* 85 are provided, each set consisting of four disks, one operating on one side edge of the blade, the second on the same edge from above, the third disk operating on the edge of the other side from below and the fourth disk operating on the last named edge from above. 90 In the machine shown the disks *p* are supposed to be adapted to hone the blades to roughly grind them. The disks *q* are supposed to be adapted to finally hone or polish the blades on the edges ground by the disks *p* and the disks *r* are adapted to strop the sharp edges honed or polished by the other disks.

The disks *p*, *q* and *r* are rotated in the desired direction by any driving means well 100 known by any expert and also the rotation of the drums or wheels *b* may be obtained by any well known driving means.

As may be well understood the rails *d* and *h* are provided with gaps *d*¹, *d*² and *h*¹, *h*² 105 alternately above and below suitable dis-

tances apart to allow the disks *p*, *q* and *r* to project into the rails to conveniently operate on the blades *m*.

The operation of the machine is as follows: The unsharpened blades are filed on the bolts *n* projecting out from the band *c* at the front end *s* of the machine. To permit this the upper rail *h* is sufficiently shorter than the lower rail *d*. The band *f* by the aid 5 of the projecting bolts *n* carries the blades along between the rails *d* and *h*, first past the disks *p* which operate on the blades to give them a rough whetting or honing, whereupon they are carried to the disks *q* 10 which finally hone or polish the blades at their cutting edge. By the last set of disks *r* the honed and polished blades are finally stropped. At the rear end *t* of the machine, the finished razor blades are paid out by the 15 band and may be taken away by any convenient manner.

The feeding of the blades at *s* may either be carried out by hand or in any known automatical manner one after the other.

20 25 Evidently the blades, while being operated on by the whetting disks, are firmly held in a perfectly steady sidewise immovable manner, so that keen sharp and regular cutting edges are obtained.

30 I claim:

1. In a razor blade whetting machine comprising a series of whetting disks, a movable endless metal band, a series of bolts on the metal band standing at a distance apart 35 corresponding to perforations in the blades to be sharpened by the said whetting disks, two guide rails spaced apart a distance equal to the thickness of the blades, one rail being grooved longitudinally to receive the ends of 40 the bolts projecting through the perforations of the blades and the other rail grooved longitudinally corresponding to the cross-section of the metal band.

2. In a razor blade whetting machine 45 comprising a series of whetting disks, two drums, a perforated endless metal band passing around the drums, a series of bolts fitting into the perforations of the metal band and standing at a distance apart corresponding 50 to perforations in the blades to be sharpened by the said whetting disks, two guide rails spaced apart a distance equal to the thickness of the blades, one rail being grooved longitudinally to receive the ends of the 55 bolts projecting through the perforations of the blades and the other rail grooved longitudinally corresponding to the cross-section of the metal band.

tudinally corresponding to the cross-section of the metal band, and to the other ends of the bolts.

3. In a razor blade whetting machine comprising a series of whetting disks, two drums, an endless metal band passing around the drums, a series of bolts on the metal band standing at a distance apart corresponding to perforations in the blades to 60 be sharpened by the said whetting disks, two guide rails spaced apart a distance equal to the thickness of the blades, one rail being grooved longitudinally to receive the ends of the bolts projecting through the perforations of the blades and the other rail grooved longitudinally corresponding to the cross section of the metal band, said rails having gaps therein to allow the whetting disks to 65 pass up to the edges of the blades. 70

4. In a razor blade whetting machine comprising a series of whetting disks, two drums, an endless metal band passing around the drums, a series of bolts on the metal band standing at a distance apart corresponding to perforations in the blades to 75 be sharpened by the said whetting disks, and provided with parallel guiding faces at one end, two guide rails spaced apart a distance equal to the thickness of the blades, one rail being grooved longitudinally to receive the ends of the bolts projecting through the perforations of the blades and the other rail grooved longitudinally corresponding to the cross-section of the metal band, said rails having gaps therein to allow the whetting disks to 80 pass up to the edges of the blades. 85

5. In a razor blade whetting machine comprising a series of whetting disks, two drums, an endless metal band passing 90

around the drums, a series of bolts on the metal band standing at a distance apart corresponding to perforations in the blades to be sharpened by the said whetting disks, the heads of the bolts having parallel sides, two guide rails spaced apart a distance equal to the thickness of the blades, one rail being grooved longitudinally to receive the ends of the bolts projecting through the perforations of the blades and the other rail grooved longitudinally corresponding to the cross-section of the metal band. 100 105
